UNITED STATES PATENT OFFICE.

CARLTON N. OGDEN, OF HOUSTON, TEXAS.

DISPLAY AND VENDING DEVICE.

1,327,771.

Specification of Letters Patent. Patented Jan. 13, 1920.

Application filed May 5, 1919. Serial No. 294,824.

To all whom it may concern:

Be it known that I, CARLTON N. OGDEN, a citizen of the United States, residing at Houston, in the county of Harris and State 5 of Texas, have invented certain new and useful Improvements in Display and Vending Devices, of which the following is a specification.

This invention relates to new and useful 10 improvements in a display and vending device.

One object of the invention is to provide a device of the character described, whereby articles of merchandise may be displayed to 15 purchasers, in such a manner that said purchasers may readily and personally select the articles which they desire to purchase without the assistance of a clerk.

Another object of the invention is to provide 20 a device of the character described, which is automatically movable, so as to bring the articles sought to be purchased within easy view and reach of the purchaser, thus making it unnecessary for the purchaser to change position or move about in 25 selecting the articles which he desires.

A further feature of the invention is to provide 30 a device of the character described, which will dispense with the necessity of delivery clerks, and help, incident to the delivery of the goods and whereby the purchaser may easily select and conveniently pay for the goods; thus eliminating unnecessary expense in making sales and making 35 it much more convenient to the purchaser to purchase and pay for the goods.

With the above and other objects in view, the invention has particular relation to certain 40 novel features of construction, operation and arrangement of parts, an example of which is given in this specification and illustrated in the accompanying drawings, wherein:

Figure 1, is a plan view of the complete 45 device,

Fig. 2, is a vertical sectional view thereof, and

Fig. 3, is an enlarged fragmentary plan view.

Referring now more particularly to the 50 drawings wherein, like numerals of reference designate similar parts in each of the figures, the numeral 1, refers to the base or floor of a storeroom, which is preferably formed of concrete, said room having the four walls 2, as shown. The numeral 3 re-

fers to a vertical central shaft whose lower end has a bearing in the bottom bearing plate 4. This shaft is rotatable and projects up through a bearing 5, which is fixed in 60 position by means of the brackets 6, which are anchored at their lower ends to the floor 1. A plurality of circular shelves 7 are provided which are concentrically arranged and spaced apart, one above the other. These 65 shelves are anchored together by means of the anchors 8, and the spaces between them are separated into separate compartments by the partitions 9, thus forming separate 70 compartments for the reception of different articles. A section 10 of the shelving is separate from, but hinged to, the remainder, so as to open and close, as shown in Fig. 3, to permit access to the interior of the ring of shelving for storing goods and placing same 75 in the respective compartments. The shelves are hung, or suspended from the top of the shaft by means of girders 11, which are secured at their inner ends to a bracket 12, carried by the top of the shaft, and which 80 radiate therefrom and whose outer ends are fastened to the shelving. Fixed to the lower end of the shaft 3, there is a relatively large screw gear wheel 13, which operates on roller 85 bearings 14, interposed between it and the plate 4. This gear wheel is in mesh with and driven by a screw gear 15, fixed upon the short shaft 16. This last mentioned shaft is operatively connected with a motor 17, through the gears 18, and is rotated 90 thereby and through this mechanism the shelving is turning. Entrance and exit passageways 19 and 20 are provided to permit 95 the entrance and exit of customers from the room. These are guarded by the turnstile 21 which permits customers to enter from the passage way 19, and to depart through the passageway 20, but prevents entrance through the latter or exit through the former. The walls of the room may be provided with storage shelves, or other storage 100 means, as 22, if desired.

The customer may enter the room, as explained, and take his station by the circular shelving, which is constantly rotating at a 105 slow rate of speed, so as to bring all the articles successively before him. As the articles pass by the customer, he may select those desired and when ready to depart, he carries said articles by the cashier, located 110 within the counter 23, alongside the exit passageway, where the articles are checked,

the stamps thereon canceled, and payment made. Each article on the shelves carries a stamp, peculiar to the proprietor, so that the purchaser may carry other articles into the store with him without causing confusion or delay when checking out.

What I claim is:

1. A device of the character described including annular shelves, spaced apart, one above the other and fixed to a concentric vertical shaft and providing a clear space within the ring of shelving, one section of the shelves being hinged so as to open and close to permit access to said space and means for 15 rotating said shaft and shelving.

2. A device of the character described, including annular shelves, spaced apart, one above the other, and fixed to a concentric vertical shaft and providing a clear space within the ring of shelving, an opening through the shelves to permit access to said space, a closure for said opening, and means for rotating said shaft and shelving.

In testimony whereof I have signed my name to this specification in the presence of two subscribing witnesses.

CARLTON N. OGDEN.

Witnesses:

R. M. SMITH,
E. V. HARDWAY.
